DESIGN FOR A CLOSURE FOR WATER CONTAINER

Letcher O. Grice, Washington, D. C.

Application April 28, 1942, Serial No. 106,733

Term of patent 3½ years

To all whom it may concern:

Be it known that I, Letcher O. Grice, United States Army, a citizen of the United States, residing at Washington, District of Columbia, have invented a new, original, and ornamental Design for a Closure for Water Container, of which the following is a specification, reference being had to the accompanying drawing, forming part thereof.

Fig. 1 is a top plan view of a closure for water container, showing my new design.

Fig. 2 is a side elevational view, and

Fig. 3 is a rear elevational view thereof.

I claim:

The ornamental design for a closure for water container, as shown.

LETCHER O. GRICE.
